[57] CLAIM

The ornamental design for a horseshoe, as shown and described.

DESCRIPTION

FIG. 1 is a top plan view of a horseshoe showing my new design;

FIG. 2 is a bottom plan view thereof;

FIG. 3 is a rear elevational view thereof;

FIG. 4 is a right side elevational view thereof, the left side being a mirror image of the right side shown; and

FIG. 5 is a front elevational view thereof.
